UNITED STATES PATENT OFFICE.

MARY D. TATE-SMITH, OF WEST ORANGE, NEW JERSEY.

BRASSIÈRE.

1,394,235.

Specification of Letters Patent. Patented Oct. 18, 1921.

Application filed November 27, 1920. Serial No. 426,698.

To all whom it may concern:

Be it known that I, MARY D. TATE-SMITH, a citizen of the United States, residing at West Orange, in the county of Essex and

5 State of New Jersey, have invented new and useful Improvements in Brassières; and I do hereby declare the following to be a full, clear, and exact description of the invention, such as will enable others skilled in the art 10 to which it appertains to make and use the same.

My invention relates to garments. It is, broadly, a combined brassière and corset cover, and its object is to provide a simple, 15 one-piece article in which all the parts are connected so that all may operate in unison and yet freely and separately.

To this end it comprises the parts and combinations recited in the appended claims.

20 In the accompanying drawings, Figure 1 is a perspective view showing the article as worn;

Fig. 2 is a vertical section, that is a section vertically through the central part of 25 the garment;

Fig. 3 is a plan view with a part of the cover removed to show the interior elastic web;

Fig. 4 is an enlarged detail on the line 30 4—4 of Fig. 3 showing the connection between the bands and central web and between the bands and the corners of the cover;

Fig. 5 is an enlarged detail on the line 35 5—5 of Fig. 3 showing the connection of the shoulder straps to the body of the cover.

10 represents an inner flexible band or web of elastic material. To this web is firmly attached at each end, a flexible waist 40 band 11 with complementary securing devices 12 at the ends constructed so that when the garment is wrapped about the form the two flexible bands will encircle the waist and cross at the back and be hooked together in 45 front, parts 10—11 being secured together by a line of stitching 11^a as shown in Fig. 4. The cover or camisole 13 is a slip of material, as satin, preferably finished at the top by a hem or hemstitch, as illustrated 50 particularly in Fig. 1 at 14. The cover and the waistbands are united by a stitch or series of stitches, 15, passing through the outer edges of each end of the band so that when the band is drawn out it will not simply 55 operate upon the inner elastic web but will also serve to draw upon each end of the

satin cover gradually spreading out the various folds, thus providing that the whole article shall be properly and smoothly adjusted without deforming any of the parts. 60

Shoulder straps 16 are attached preferably as illustrated, particularly in Figs. 2 and 3.

The general purpose of the brassière is, as usual to confine the bust and reduce its 65 size when necessary, while at the same time it is particularly adapted to the present low cut style of dress. The winding application of the garment in connection with the hooks which may be readily adjusted with relation 70 to each other enables the article to accommodate itself to any change in the figure, and to different figures, and to retain its binding properties. The shoulder straps may be so attached as to enable the garment 75 to be adjusted upon the figure and to regulate the height of the brassière.

The cover can readily be removed for cleansing or replaced without dismantling the main body parts, and it keeps clean the 80 elastic web and acts as a camisole.

The fact that the device is a strip to be worn as a belt about the body enables the confining of the figure in a "straight line" thus producing the much desired young and 85 girlish figure. There is, in fact, no distinct part to this garment except in so far as the interior elastic enables the self-adjustment of the strip so as not to call for the usual pockets or fitting devices, etc. No draw cord 90 is required and the device is, in effect, a single strip to be drawn about the body. The garment, in short, meets the present demand for a brassière that may be worn with evening dress and tends to conform to the present approved fashionable figure for women. It has the singular advantage of so exactly 95 fitting the figure that the bust is properly confined or reduced while at the same time no portion of the brassière shows at the back, the flexible band portions encircling the body and passing around the back at a point below the top of the belt of even the extreme low-cut evening dress.

While the garment is thus adapted and 105 designed for the purpose of confining and reducing the figure, its elastic qualities coupled with the flexible attaching devices at the same time afford proper room for breathing. My brassière molds itself upon the 110 body everywhere without undue pressure at any given point. In fact, being a single

straight garment before application, it adapts itself to the figure while at the same time securing all the results of an ordinary brassière, and also the particular result of being suited for evening wear.

I call special attention to the fact that the garment as presented for sale is a continuous, flexible straight strip, convenient in the shop and boudoir and that its structure is such as not to call for shaped pockets, bindings, or any similar devices which so frequently defeat the objects of such a garment.

The fact that the flexible bands secure the garment about the waist while the shoulder straps hold it from above gives the garment great range of application, yielding flexibly with the movement of the body while at the same time preventing displacement of the garment in either direction.

The construction of the garment is such as to readily lend itself to those elegancies of finish which peculiarly fit it for use with handsome gowns, such as ball-gowns or tea-gowns.

I claim:—

1. In a brassière, the combination of an

elastic body supporting band, a cover enveloping the body band and flexible securing bands attached to the body supporting band and cover.

2. In a brassière, the combination of an elastic body adapted to form the front of a corset structure, comparatively narrow securing straps attached thereto and adapted to be wound about the body and secured together, and a cover surrounding the elastic body portion and extending partly over the ends of the flexible attaching band.

3. A brassière adapted to be wound about the body of the wearer, comprising a central elastic body band, flexible bands on each side of the central band and adapted to be wound about the waist, and a cover for the elastic band adapted to serve as a camisole.

4. In a brassière the combination of an elastic body band, a gathered cover surrounding the elastic body band, flexible bands secured to the body band and the cover and shoulder straps secured to the cover.

In testimony whereof I affix my signature.

MARY D. TATE-SMITH.
